HANGING PLANTER

Janet M. Weiss, P.O. Box 2, Fort Bragg, Calif. 95437

Filed Nov. 1, 1974, Ser. No. 519,894

Term of patent 14 years

Int. Cl. D11—02

U.S. Cl. D35—3 A

FIG. 1 is a perspective view of a hanging planter of my new design;

FIG. 2 is a top plan view of the planter;

FIG. 3 is an elevation view of the planter;

FIG. 4 is a bottom plan view of the planter; and

FIG. 5 is a partial cross-section taken on line 5—5 of FIG. 3.

The broken lines are shown for illustrative purposes only.

I claim:

The ornamental design for a hanging planter, as shown and described.
